COLLAPSIBLE BOX WITH LEGS
 Lewis N. Trinnal, 2214 James St., Cayce, S.C.
 Filed Apr. 17, 1963, Ser. No. 273,601
 2 Claims. (Cl. 312—213)

This invention primarily relates to a multi-purpose container which is specifically adapted to be collapsed from an upright enclosure to a knocked down position to facilitate storage and shipping thereof.

It is an object of this invention to provide a container which may be spaced above a supporting surface but yet comprising means allowing it to be collapsed for shipping or storage purposes.

Another object of this invention in accordance with the preceding object specified, is the provision of a container which comprises a pair of opposing end and side walls abutting a bottom wall, the side walls and end walls of which may be collapsed to a position overlying the bottom wall thereof thereby reducing effectively the space the container is adapted to occupy.

Yet another object of this invention resides in the fact that once the container is used to enclose various objects, means may be provided to prevent collapse of the container.

A still further object of this invention comprises the fact that the side walls of the container are adapted to be collapsed to an overlying position by having the side walls thereof pivoted on axes which are spaced above each other.

Another object of this invention resides in the provision that the end walls of the container may be oriented coplanar with the side walls whereby effective retaining means may be extended through the end walls and side walls to provide a strong and durable enclosure and prevent collapsing thereof.

Yet another object of this invention resides in its simplicity of construction but efficient use for the purpose for which it has been conceived.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a perspective view of the container comprising the subject matter of the instant invention.

FIGURE 2 is a longitudinal sectional view taken substantially on the line 2—2 of FIGURE 1.

FIGURE 3 is a sectional view taken substantially on line 3—3 of FIGURE 2.

FIGURE 4 is a view similar to FIGURE 2 but shows the container in a collapsed condition, for shipping or storage purposes.

FIGURE 5 is a sectional view taken substantially on the line 5—5 of FIGURE 4.

FIGURE 6 is a fragmentary sectional view taken substantially on the line 6—6 of FIGURE 1 and illustrates the means utilized in conjunction with the present invention to prevent collapsing of the side and end walls of the container when it is being used as an enclosure.

Referring now to the drawings in detail, the container comprising the subject matter of the instant invention is generally designated by the numeral 10 and comprises a bottom wall 12, a pair of opposed side walls 14 and 16, and a pair of opposed end walls 18 and 20. The bottom wall is substantially hollow as shown at 22 but comprises a central brace or strut 24 extending between the edges thereof. A supporting wire screen 26 extends the full length of the bottom wall 12, in order to enable objects to be supported thereon.

2

The bottom wall 12 extends intermediate a first pair of legs 28 and 30 and a second pair of legs 32 and 34. In this manner, the container may be substantially spaced above a supporting surface whereby the container is used to support trash or the like, and stray animals cannot get into the interior.

The side walls 14 and 16 are adapted to extend between the legs 28, 32 and 30, 34 and the wall 14 has a bottom edge abutting the bottom wall 12. It will be noticed, however, that the side wall 16 is formed of two pieces 31 and 33. The piece 33 is stationary and is held in place by means of a pair of anchor pins 35 or the like when the container is used as a receptacle. The piece 31 is adapted to seat on the piece 33 in this position, but when the box is collapsed, as shown in FIGURE 5, the piece 33 is removed and stored beneath the container by means of a pair of spring clips such as 37 attached to the bottom wall 12. Like the bottom wall 12, the side walls 14 and 16 are also hollow, but are closed by means of a fine wire mesh screen 36 and 38 respectively. Therefore, the user of the container can readily observe the level of the contents placed therein.

The end walls 18 and 20 of the container are each formed of a two-piece construction. A lower portion 40 and 42 of the end walls 18 and 20 respectively, extend intermediate adjacent legs 28, 30 and 32, 34 and are rigidly joined thereto. The upper portions of the end walls 18 and 20 designated by the numerals 44 and 46 respectively, are pivotally mounted intermediate the legs 28, 30 and 32, 34 as will hereinafter be described and further comprise laterally extending flanges such as generally shown by the numeral 48. The laterally extending flanges 48 form upright extensions of the legs 28—34 and terminate coplanar with the side walls 14 and 16. Suitable anchoring pins such as shown at 50 and as more clearly shown in FIGURE 6, are adapted to extend through aligned openings 52 in the end walls and 54 in the side walls to effectively rigidify the structure and prevent the same from collapsing.

A removable lid 56 having a handle element 58 centrally mounted thereon is supported on the top edges of the end walls and side walls. This effectively completes the enclosure of the container.

Referring now to FIGURES 4 and 5, it will be appreciated that the container end walls and side walls may be collapsed to an overlying position to effectively reduce the space which the container occupies. The top portions 44 and 46 of the end walls are pivoted by means of pins or the like about an axis 60 and 62 respectively. The pivot pins 50 extend through the side edges of the leg portions just below the laterally extending flanges 48 of the end walls and terminate in said end walls. The side wall 14 is adapted to pivot about an axis 64 by means of pins or the like extending through one of the faces of the legs 28 and 30 and terminating in the edge portions of said side wall. The portion 31 of the side wall 16, after the portion 33 has been removed, is pivoted about an axis 66 which lies in a plane substantially above the axis 64 whereby upon pivoting said side walls to overlie the bottom, the side wall 16 will overlie the side wall 14 in collapsed position rather than interfering therewith. As the pins comprising the axis 64, the pins utilized to define the axis 66 pass through the outer face of the legs 30 and 34 and terminate in a side edge of the portion 31 of the side wall 16.

The collapse of the container to its knocked down position should now be readily apparent. The pins 35 and 50 are first removed and the portion 33 of the side wall 16 is stored beneath the bottom wall 12. The side wall 14 is then pivoted about the axis 64 to a position overlying the bottom wall 12. Then, the portion 31 of the side wall 16 is pivoted about the axis 66 to a position as

shown in FIGURE 5, wherein it overlies the side wall 14. The end wall portions 44 and 46, may then be pivoted about the axes 60 and 62 respectively to a position atop the side wall 16. The lid is then once again placed on the collapsed structure as shown in FIGURES 4 and 5, therefore forming a compact knocked down container occupying substantially less space than when in use position. It will be appreciated that by making the side wall 16 of two pieces, the rectangular shape of the container is preserved in its knocked down condition thereby providing for ease of handling and shipping.

It should be noted that suitable handles 68 and 70 may be mounted on the stationary portions 40 and 42 of the end walls, whereby the container may be readily carried by the user. It should also be noted that the bottom edges of the flanges 48 and the top edges of the leg portions 28-32 are rounded as shown at 72 and 74.

It should be appreciated that a container of this type can be adapted to a multiplicity of uses. Also, suitable wheels may be placed on the bottoms of the legs 28-32 whereby the container may be wheeled from place-to-place. The legs of the container may also be constructed of portions which can be pivoted to underlie the bottom wall for conserving space, if desired. Due to its simplicity of construction, the container may be made of any practical material such as wood, or molded plastic or aluminum.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A collapsible container comprising an elongated rectangular horizontal bottom having opposed end edges and opposed side edges; a pair of flat elongated legs secured to each end edge adjacent the opposite ends thereof, each leg being orientated vertically and having one longitudinal edge thereof aligned with, or in the same vertical plane as, the adjoining side edge of the bottom, said legs projecting both vertically above and vertically below the bottom, the projection of the legs vertically below the bottom being sufficient so as to space the bottom in substantial spaced relation to a supporting surface; a pair of end walls, each of said end walls being of the same thickness as the legs and consisting of a lower

portion and an upper portion, each lower portion being fixedly secured to an end edge of the bottom between and coplanar with the legs thereon, the upper and lower edges of each lower portion terminating inwardly of the upper and lower ends of the legs, each upper portion being pivotally secured to and between the pair of legs secured to one end edge for movement between a first vertical position coplanar with the legs and the corresponding lower portion, and a second inwardly extending horizontal position with the lower edge of the upper portion coplanar with the outer face of the corresponding lower portion, each upper portion including a pair of integral laterally extending coplanar side flanges forming, in the first vertical position, vertical coplanar extensions of the corresponding legs; and a pair of side walls, each side wall being positioned along one side edge of the bottom and being pivotally mounted on and between one leg on one end edge of the bottom and the corresponding leg on the other end edge for movement between a first vertical position with its outer face coplanar with the side edge, and a second inwardly extending horizontal position with its lower edge coplanar with the side edge, said side walls being pivotally mounted in vertically offset planes so as to enable one to overlie the other in their horizontal positions, said end wall upper portions being pivotally mounted in the same plane vertically above the plane of pivotal mounting of the upper side wall; the projection of the legs vertically above the bottom being approximately equal to the combined height of the horizontally positioned side and end walls.

2. The structure of claim 1 including a pair of handles, one fixed to each end wall lower portion, each handle projecting laterally outward from its corresponding lower portion.
